Primary Examiner — Andrew T Nemeth

(22) Filed: May 6, 2021

(74) Attorney, Agent, or Firm — McAndrews, Held & Malloy, Ltd.

Related U.S. Application Data

CLAIM

(63) Continuation of application No. 29/722,810, filed on Jan. 31, 2020, now Pat. No. 922,409, which is a continuation-in-part of application No. 16/779,540, filed on Jan. 31, 2020, now Pat. No. 10,872,502.

The ornamental design for a display screen or portion thereof with graphical user interface, as shown and described.

(30) Foreign Application Priority Data

DESCRIPTION

Sep. 20, 2019 (AU) 2019232939
Sep. 20, 2019 (AU) 2019232942
Sep. 23, 2019 (AU) 2019236613

FIG. 1 is a front view of a display screen or portion thereof with graphical user interface showing our new design according to a first embodiment;

(51) LOC (13) Cl. 14-04

FIG. 2 is a front view of a display screen or portion thereof with graphical user interface showing our new design according to a second embodiment;

(52) U.S. Cl. D14/486

FIG. 3 is a front view of a display screen or portion thereof with graphical user interface showing our new design according to a third embodiment; and,

(58) Field of Classification Search

FIG. 4 is a front view of a display screen or portion thereof with graphical user interface showing our new design according to a fourth embodiment.

USPC D14/485-495

The dashed broken line perimeter in the drawings illustrates a display screen or portion thereof and forms no part of the claimed design. The remaining dashed broken lines in the drawings illustrate portions of the graphical user interface that form no part of the claimed design.
